MEAT HOOK

Allan G. Serle, Union, N.J., assignor to Celanese Corporation, New York, N.Y., a corporation of Delaware

Filed Nov. 8, 1967, Ser. No. 9,337

Term of patent 14 years

(Cl. D11—1)

FIG. 1

FIGURE 1 is a side elevation, both sides being identical, of my meat hook;

I claim:

The ornamental design for a meat hook, as shown and described.
